UNITED STATES PATENT OFFICE.

CHARLES O. MOYER, OF LOCK HAVEN, PENNSYLVANIA.

AUTOMATIC RAILWAY GATE.

Application filed December 3, 1926. Serial No. 152,499.

This invention relates to railway safety devices and particularly to roadway and railway crossing gates and signals.

An object of this invention is to provide a collapsible gate and particularly a gravity collapsing means.

A further object is to provide an improved anchoring means intermediate the gate pivots.

A further object is to provide an improved gate actuating means embedded beneath the gate.

A further object is to provide a combined gate and immediate and remote signal cooperative with the gate.

A further object is to provide a simplified and efficient drive for the gate which is protected from elemental conditions and to eliminate a shaft on the gate connecting the drive.

A further object of the invention is to provide a cushion and improved form of cushion for the gate.

With the foregoing and other objects in view, I have invented the device shown in the accompanying drawings, in which:

Figure 1 is a sectional view, through a roadway showing my gate structure partly in section and partly in elevation with the gate members in reverse position to each other.

Fig. 2 is a side view of the gate in closed position.

Fig. 3 is a plan view.

Fig. 4 is a detail sectional view of one of the gate sections.

Fig. 5 is a detail view showing the interlocking feature of the gates.

Fig. 6 is a plan view of Fig. 5, and

Fig. 7 is a plan view of the gate installation respecting its location to a railroad.

Like reference characters indicate like parts throughout the several views and in the specification, in which, I provide a tunnel 2, transversely beneath the roadbed 3, which roadbed is then formed by a ceiling 4 for the tunnel. Midway of the tunnel 2, I mount a motor 5, which is preferably of the reversible type, and extending from which motor are shafts 6 and 7, carrying respectively spur gears 8 and 9, which gears co-mesh respectively with gears 10 and 11 upon their respective shafts 12 and 13. The shafts 12 and 13 being suitably journaled in standards 14, the standards 14, being anchored to the floor 15 of the tunnel 2.

Carried by the shafts 12 and 13, are respectively worms 16 and 17, co-meshing respectively with segmental worm gears 18 and 19, the segmental gears being upon the peripheries of counter-weights 20 and 21, which weights are carried by shafts 22 and 23. Shells 24 and 25 respectively support the shafts 22 and 23 and are provided with slots 26 and 27 for the passage of the gate bars 28 and 29, which bars are anchored respectively to the counter-weights by fitting in sockets 30', and are reinforced by brackets 32. Pivots pendant from the main bars 28 and 29, are links 30, pivotally carrying secondary bars 31, beneath the ends of which bars 31, are pins 31', adapted to engage suitable sockets in the ceiling 4.

Near the free ends of the bars 28 and 29, are arcuate springs 33, adapted to cushion the gate in striking a roadbed. On the free end of the bar 28, is a pendant pin 34, and on the free end of the bar 29 is a socket 35, for the pin 34.

The motor 5 is suitably connected with suitable track switch members, as by wires 36, which, in turn, are suitably connected with an immediate light signal and a remote semaphore. The signal 37, is mounted on a rod 38, mounted in a socket 39, upon each of the casings 24 and 25 and is connected by suitable wiring means with lights 40, carried by the springs 33.

In operation upon energizing the motor 5, by means of the connecting shafts and gears, the weights 20 and 21, are turned in predetermined directions in opposite direction to each other, thereby lowering or lifting the gates, as desired. As the gates rise, the bars 31, gravitate with the links 30, thereby collapsing the gates and as the gates lower the bars 31, and links 30, gravitate to extend the gate downward. The pins 31', automatically seat in sockets 4' in the ceiling 4, and the pin 34, automatically seats in its socket 35, thereby rigidly interlocking the gate bars 28 and 29, and anchoring them to the ceiling 4.

Having described my invention that which I claim to be new and desire to secure by Letters Patent is:

1. A gate comprising main bars, motor driven means for simultaneously swinging the bars upwardly or downwardly, secondary bars, link connections between each main bar and one of the secondary bars, pins depending from the stationary bars, there be-

ing sockets for the reception of the pins when the bars are swung downwardly to closed position, and cooperating means on the ends of the main bars for interfitting 5 when the bars are lowered to closed position, said means and the pins constituting means for holding the gate against lateral swaying when closed.

2. The combination with spaced segmental 10 gears and recessed counterweights carried thereby, of means for simultaneously rotating the gears to swing the counterweights toward or from each other, main bars fitted in the recesses in the counterweights and 15 movable with the gears and counterweights, secondary bars, links providing floating connections between the secondary bars and the main bars, cooperating means on the free ends of the main bars for holding said bars 20 against lateral shifting while in lowered or closed position, and means carried by the secondary bars for holding them against lateral shifting while in lowered position.

3. The combination with spaced segmental gears and counterweights carried thereby, of 25 a recessed roadbed between the gears, means beneath the roadbed for simultaneously actuating the gears to swing the counterweights toward or from each other, main bars extending from the counterweights 30 and movable therewith, secondary bars, links providing floating connections between each secondary bar and one of the main bars, means on the secondary bars for entering the recesses in the roadbed when the bars are moved to lowered position thereby to hold said bars against lateral shifting, cooperating means on the free ends of the main bars for holding said bars against lateral 35 shifting when brought to closed position, and yielding supports carried by the free ends of the main bars for engagement with the roadbed when the bars are brought to closed 40 position.

In testimony whereof I affix my signature.
CHAS. O. MOYER.
